UNITED STATES PATENT OFFICE.

JOSEPH J. MAGRADY, OF CHICAGO, ILLINOIS.

PLATFORM SCALE.

Application filed August 11, 1922. Serial No. 581,168.

To all whom it may concern:

Be it known that I, JOSEPH J. MAGRADY, a citizen of the United States of America, residing at Chicago, in the county of Cook 5 and State of Illinois, have invented certain new and useful Improvements in Platform Scales, of which the following is a specification.

My present invention relates generally to 10 pit scales, that is wagon and automobile scales as well as scales for railroad use and thus to what are commonly known as heavy capacity scales, the improvements having to do more particularly with the pit levers, 15 their connections and supports, with the object in view of providing for direct transmission through simple effective levers and lever connections as well as supports in order to do away with the well known disadvantages of scales of this type resulting 20 from the usual complicated levers, lever connections and supports.

A further object is the provision of 25 means whereby an accurate effectively operating scale may be maintained without the present disadvantages of frequent shut down for repair and substitution of parts and whereby durability, economy and uniformly accurate operation will be promoted. 30 It is a well known fact that in connection with railroads, mines and other industries requiring heavy capacity scales especially those of fifty or more feet in length, great difficulty is encountered in maintaining the 35 scales as at present constructed in a uniformly accurate condition. In fact constantly increasing inaccuracy becomes noticeable almost at once on account of the great number of levers and lever connections 40 necessitated by the systems now in use and on account of the rapid collection of dirt and débris upon the complicated lever connections which not only promotes inaccuracy but which necessitates frequent repair 45 and substitution in the course of which the scales cannot be used.

My present improvements aim to eliminate these defects and do away with the 50 complicated indirect levers and connections now in use and to reduce to a minimum the number of levers required and in particular the number of bearings and connections between the levers and my invention further aims to protect such bearings and connections as are employed, to the end that deterioration from weather and wear from the

approachment of dust, dirt and foreign materials will be almost entirely eliminated.

A still further object is the provision of 60 a construction in which the bolting and riveting of working parts is eliminated and all the parts are held properly in position and in place by their own weight so that all parts are capable of repair and substitution with little trouble and at the expense of 65 minimum time during which the scale must be out of commission.

In the accompanying drawings which 70 illustrate my present invention and form a part of this specification,

Figure 1 is a top plan view of the eleven lever type of scale with the scale deck removed, showing the various levers in place,

Figure 2 is a sectional side view thereof, 75

Figure 3 is an enlarged end view, partly in section,

Figure 4 is an enlarged top plan view of 80 a portion of the levers at one end of the scale,

Figure 5 is a side view of the levers at one 85 end of the scale,

Figure 6 is a sectional view through one of the T-bearing supports taken substantially on line 6—6 of Figure 7,

Figure 7 is a bottom plan view of the support of Figure 6 with the T-bearing support in place,

Figure 8 is a central section through another of the T-bearings,

Figure 9 is a top plan view of the T-bearing shown in Figure 8,

Figure 10 is a central section through one of the bearing plates of the supporting pedestals,

Figure 11 is a top plan view of the bearing plate of Figure 10, and

Figure 12 is a top plan view of the five lever type of scale showing the arrangement of levers for a comparatively short scale.

Referring now to these figures and particularly to the lengthy form of scale as applied for instance to railroad and lengthy platform use, and shown in Figures 1 to 11 inclusive, I have shown the beam actuating lever 15 or what is commonly known as a fifth lever, whose smaller outer end, projecting laterally beyond the main portion of the scale pit, may have any suitable connections with a scale beam (not shown), pivotally supported at its inner end, and pivotally engaged and depressed in action by the inner end of a pair of longitudinally disposed and

aligned connecting levers 16. Each of these connecting levers 16 is identical in structure and, like the beam actuating lever 15, preferably of oval shape in cross section, excepting where the connections are made for the major portion of the length thereof and of tapering form. By virtue of the oval shape, the actuating connections, that is those connections engaging the levers 16 adjacent to their outer ends and the connections between the inner ends of these levers and the beam actuating lever 15, may be extended upwardly into the levers and in this way housed to an extent sufficient to protect the same from the elements and from dirt and moisture dropping thereon.

The main supporting levers 17 are preferably of tapering tubular form and, in accordance with my present invention, are arranged in groups adjacent to the opposite ends of the scale, each group including four such levers in angular relationship as shown so that the levers of each group converge toward one another in an inward direction and have pivotal connections at their inner ends with the respective connecting lever 16 adjacent to the outer pivotally supported end of the latter.

For the above purposes it will be noted that each of the main supporting levers 17 is independently mounted and supported at its enlarged outer end 18 and is engaged by the scale deck or platform 19 adjacent to its said outer enlarged end 18 while its smaller inner end loosely engages a hanger or other connection 20 depending from a link 21, the latter in turn extending upwardly into the respective connecting lever 16 and over a knife bearing 22 disposed and mounted transversely through said lever 16 at a point properly spaced from its outer similarly disposed and mounted knife bearing 23, the latter like the knife bearing 24 at the inner enlarged end of the beam actuating lever 15, resting upon a steel 25 located in the grooved upper end of a T-bearing 26 the lower surface of the latter of which as seen in Figures 8 and 9, is recessed as at 27 to coact with the upper surface recesses 28 of a bearing plate 29 secured upon the upper supporting surface of a truncated conical supporting pedestal 30 in practice preferably formed of concrete, each pedestal being independent of the other pedestals and of the remaining structure of the pit so that slight displacement of the walls or base of the pit or of portions thereof will not affect the proper bearing and support of these levers nor their adaptability to freely vibrate in all directions upon the bearing balls disposed between each of the bearing plates 29 and its companion supporting T-bearing 26 and within the recesses 27 and 28. It will be noted that each bearing plate 29 has a surrounding upstanding protecting flange 31

and that each lever supporting T-bearing 26 is of slightly greater diameter than the corresponding bearing plate 29 and has a surrounding and depending protecting flange 32 adapted in practice to overlap the flange 31 of the bearing plate and thus effectively house and protect the ball retaining space between these parts.

The outer enlarged end 18 of each of the main supporting levers 17 has a downwardly opening recess 33 and has near this recess an outwardly opening recess 34 and is provided with transverse knife bearings at the bases of these recesses, the outer downwardly opening recess receiving one of the T-bearings 26 supported by means of balls 35 upon one of the bearing plates 29, the latter secured upon a pedestal 36 similar in all respects except as to height, to the pedestals 30. The inner recess 34 of each of these main levers 17, which opens upwardly, receives the depending portion of a T-bearing 37 which as shown in Figure 7 is seated at its upper portion against cushion members 38 within an enlarged bearing plate 39 secured to the lower surface of one of the deck beams 40 and having a surrounding and depending flange 41 which as clearly seen protects the T-bearing 37 from falling dirt and moisture.

Thus it is obvious that by virtue of the support in connection with the levers as described, pressure in action caused by lowering of the scale deck 19 will be applied directly through the main levers 17 and the connecting levers 16 to the center of the scale where the connecting levers engage the scale beam actuating lever 15 and it is to be understood that where but a five lever type of scale is desired I may group the main supporting levers as shown in Figure 12 where the levers are indicated as 42 and directly connected at their inner ends to a beam actuating lever 43 so that the parts are thus identical with those previously described except that the connecting levers 16 are omitted, levers 42 and 43 being constructed and supported like the levers 15 and 17 of the eleven lever type of scale shown in Figures 1 to 11 inclusive.

It thus becomes obvious that among its many advantages, my improved scale transports the weight direct from the corners to the center of the scale, that is as direct as it is possible to do so and each lever is entirely independent instead of paralleling and depending upon other levers so that all of the usual torsion or twisting movement of parts, such as exists for instance in a pipe lever system is eliminated and all tendency of tipping of levers is likewise removed so as to insure even bearings at all times.

I claim:

1. In platform scales, a centrally located transversely extending beam actuating lever,

a pair of connecting levers pivotally supported at their outer ends and extending longitudinally in alinement upon opposite sides of, and connected at their inner ends to, the said beam actuating lever at a point intermediate the ends of the latter, and main supporting levers converging in groups adjacent to the outer ends of said connecting levers, each of said main levers being independently mounted and connected at the center of its respective group to the respective connecting lever intermediate the ends of the latter.

2. In platform scales, a series of main supporting levers angularly related in a group and converging to the center of the group, said levers being of tubular tapering form and having lengthwise spaced transversely disposed knife bearings at their outer ends, a supporting pedestal on which

the outer end of each lever is mounted having means to receive the outer knife bearing, and platform-carried means to engage the inner knife bearing.

3. In platform scales, a series of main supporting levers arranged in a group in convergent relation, and a lever to which the inner ends of said supporting levers are connected at the center of the group, each of said main supporting levers having an independent mounting at its outer end including a supporting pedestal, and bearing members on the pedestal one of which is engaged by the lever, having means to permit vibration of the lever horizontally in all directions.

In testimony whereof I have affixed my signature.

JOSEPH J. MAGRADY.
